BUILDING CONSTRUCTION

Hubert O. Carroll, Painesville, Ohio

Application April 1, 1936, Serial No. 72,139

16 Claims. (Cl. 20—53)

In building structures, the matter of a sufficiently satisfactory construction permitting windows and the like of casement type has been a difficult problem. Multitudinous efforts have been made to bring about improvement in this direction, but the problem of an arrangement permitting easy opening as desired, coupled with adequate weather proofness, has remained serious. In accordance with the present invention however, a construction may now be had which eliminates these drawbacks and provides a serviceable and neat interior and exterior, and without undue cost.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:

Fig. 1 is an interior elevational view of construction embodying the invention; Fig. 2 is a sectional detail, on a large scale, taken on a plane substantially indicated by line II—II, Fig. 1; Fig. 3 is a fragmentary perspective view of a portion of the structure shown in Fig. 1; Fig. 4 is a similar view with the movable parts in different or opened position; Figs. 5 and 6 are enlarged elevational details, in closed and open position respectively; Fig. 7 is an enlarged fragmentary detail in elevation; and Figs. 8 and 9 are edge views of the same structure, showing different positions.

Referring more particularly to the drawing, there is shown a building wall 2, having a framed opening, with framing 3, and a swingable member 40 or panel P therein, of casement type, as a window or door, a window being illustrative. Such member is mounted to swing inwardly, by means of the hinges H, and at the bottom is a footing-abutment 5, illustratively a sill, such footing-abutment being beveled outwardly and downwardly as at 6, Fig. 2, while the adjacent lower rail 7 of the coating panel member or window P is matingly beveled, whereby to wedgingly engage and tighten on being set into closed position. The swingable member P or window is adapted to raise vertically so as to clear the abutment 5, as illustrated in dotted line position in Fig. 2, thereby allowing of its being swung open inwardly regardless of the existence of the footing abutment 5. For this, the member P or window sash

is carried on the hinges H which are so mounted as to have a controlled vertical movement without interfering with their hinge action. While the precise detail for accomplishing this may vary, a desirable construction involves a hinge member 8, Fig. 4, fastened to the edge of the stile 9 of the window sash or door, the lower hinge member 8' being similarly attached. The mating hinge members 10, 10', are carried by the framing opening, and in a suitable mounting 10 thereon to allow the afore-mentioned vertical movement, one desirable way of accomplishing this being by a metal plate 11 fastened to the casement by suitable means, as a series of screws 12, the hinge member 10 then being slidably carried, as by a pin and slot connection, headed pins or rivet-like members 14, Figs. 5 and 6, being secured to the hinge member and travelling in cam slots 15 which are suitably angularly inclined for such purpose. The hinge member 10, and with it the entire sash P may thus move up and down in a range of excursion permitted by the length of the slots 15, and by reason of the cam action supplying outward direction thereof, the sash P is pressed tight against the stops 13 of the frame. At the same time the lower rail 7 is pressed wedgingly tight against the foot-abutment bevel 6, Fig. 2, when the hinge and sash member are moved down in the lowermost position. Suitable means is provided for conveniently raising and lowering the movable hinge member and its carried sash member P. While the precise detail of this may vary, a convenient arrangement is a lever to raise the panel or sash P and being attached at some desired point. For instance lever 16 and a link 17 connecting from the lever to one of the headed pins 14 of one of the hinges, say the upper hinge 10, the lever 16 being suitably fulcrumed as at 18 and thereby mounted on the frame-engaging plate 11, and the link 17 being pivoted as at 19 to the end of the lever. Desirably, a cover plate 20 may be secured to the frame-plate 11, thereby reinforcingly mounting and protecting the movable pivot joint. The lever 16 terminates in a suitably shaped handle 21, and may be of relatively thin unobtrusive form, such as to close up inconspicuously into a slight recess between the stile of the sash and frame. The lower hinge member 10', capable of a corresponding vertical movement, is mounted on a metal plate 23, which may be a separate plate or an extension of the plate 11. The plate 23 is similarly fastened to the framing, as by screws 24 and in this plate again there are cam-slots 15', the hinge member 10' being slidably mounted 55

with respect thereto by headed pins or rivet-like members 14', thereby duplicating the movement course of the hinges 10 above.

On account of the range of vertical movement of the panel member or sash P, a cooperating locking or holding means is applied on the other stile 26. Preferably, the construction here may involve a pivoted drop latch, pivoted at 27 (Fig. 8) on the edge of the stile 26, and having an angular operating handle 28, while the latch 29 projects laterally. Desirably, the latter is provided by an anti-friction roller 30, as a sleeve. Coacting with the latch 30 is the catch-member 31 having an incline 32 on which the latch may ride up, and a recessed slot 33 in which it may seat down. This slot is particularly deep, sufficiently so that the casement panel or sash may be lifted up to its highest position and then have the latch 30 manipulated to raise and clear it from the catch member 31. The slot recess 33 is slightly angularly inclined so as to tighten the sash as it is closed. For further safeguarding and tightening the upper end of the sash, a suitable inter-engaging packing is employed, and preferably this may take the form of interlocking members 35, 36, on the frame and on the sash respectively, these being so positioned that when the sash member is in its uppermost position, the interlocking packing strips are clear of each other, and when the sash is set down to its lowermost position, these members interlock and tighten the joint.

With the casement panel or sash P in its closed position as shown in Fig. 1, the lower rail 7 is seated with its inner margin wedgingly tight against the bevel 6 of the sill or foot-abutment, and the upper packing members 35, 36, are in interlocking engagement, and the pivoted catch 29 is seated in the slot recess 33 of the holding-catch member 31, the engagement of the entire panel or sash being particularly tight against the coacting frame work. By manipulation of the handle 21 of the lever 16, the hinge 10 is raised, and with it the entire casement panel or sash, and without manipulation of the catch or lock 28 the panel or sash member P then stands up clear of the footing-abutment or sill 5, and a crack for ventilation is provided. At the same time there is similarly a ventilating crack at the top. The latch 29 however still holds the sash against opening, this by reason of the long excursion permitted in the recess slot 33. To open the casement panel or sash, the handle 28 of the latch is raised, so as to clear the latter from the recess slot of the catch member 31, and the panel or sash can then be swung open as indicated in dotted lines in Fig. 1. It will be noticed that it swings thus when in its elevated position and clearing the footing abutment or sill 5. To close the sash, the reverse movements are employed.

It is thus seen that a particularly tight and weatherproof construction is had, although permitting the convenience of an inwardly-opening casement, and with the further advantage of permitting ventilation without completely opening.

Other modes of applying the principle of the invention may be employed, change being made as regards the details described, provided the features stated in any of the following claims, or the equivalent of such, be employed.

I therefore particularly point out and distinctly claim as my invention:—

1. In building construction, a framed wall-opening; an inwardly-swingable sash therein; and means for forcing said sash transversely to

its general plane and tightening the sash in the framed opening, including a footing-abutment to engage the inside lower margin of the latter and being beveled downwardly and outwardly to wedge a mating bevel on the lower margin of the sash, hinge members on the sash stile and mating hinge members on the framed opening, metal plate members on the latter carrying the mating hinge members, inclined cam slots in said metal plate members, headed pin fastening means for said latter hinge members movable up and down in said slots, a lever and a link therefrom to one of said latter hinge members for raising and lowering it and the attached sash, said lever being foldable inconspicuously adjacent the sash, a pivoted drop latch on the unhinged stile of the sash having a lift handle and an anti-friction roller extending laterally, a receiving plate therefor on the wall-opening having an inclined cam slot extending deeply such as to be capable of manual release of the latch-roller when the sash is in its raised position, and inter-locking packing members on the upper margin of the sash and wall-opening coacting at the outside of the sash when in its lower position.

2. In building construction, a framed wall-opening; an inwardly-swingable sash therein; and means for forcing said sash transversely to its general plane and tightening the sash in the framed opening, including a footing-abutment to engage the inside lower margin of the latter and being beveled downwardly and outwardly to wedge a mating bevel on the lower margin of the sash, hinge members on the sash stile and mating hinge members on the framed opening, metal plate members on the latter carrying the mating hinge members, inclined cam slots in said metal plate members, headed pin fastening means for said latter hinge members movable up and down in said slots, a lever and a link therefrom to one of said latter hinge members for raising and lowering it and the attached sash, a pivoted drop latch on the un-hinged stile of the sash having a lift handle and a latch member extending laterally, a receiving plate therefor on the wall-opening having an inclined cam slot extending deeply such as to be capable of manual release of the latch when the sash is in its raised position, and inter-locking packing members on the upper margin of the sash and wall-opening coacting at the outside of the sash when in its lower position.

3. In building construction, a framed wall-opening; an inwardly-swingable sash therein; and means for forcing said sash transversely to its general plane and tightening the sash in the framed opening, including a footing-abutment to engage the inside lower margin of the latter and being beveled downwardly and outwardly to wedge a mating bevel on the lower margin of the sash, hinge members on the sash stile and mating hinge members on the framed opening, metal plate members on the latter carrying the mating hinge members, inclined cam slots in said metal plate members, headed pin fastening means for said latter hinge members movable up and down in said slots, a lever and a link therefrom to one of said latter hinge members for raising and lowering it and the attached sash, said lever being foldable inconspicuously adjacent the sash, a pivoted drop latch on the un-hinged stile of the sash having a handle and a latch member extending laterally, and a receiving plate therefor on the wall-opening having an inclined cam slot extending deeply such as to be capable of manual release

of the latch when the sash is in its raised position.

4. In building construction, a framed wall-opening; an inwardly-swingable sash therein; and means for forcing said sash transversely to its general plane and tightening the sash in the framed opening, including a footing-abutment to engage the inside lower margin of the latter, hinge members on the sash stile and mating hinge members on the framed opening, metal plate members on the latter carrying the mating hinge members, inclined cam slots in said metal plate members, headed pin fastening means for said latter hinge members movable up and down in said slots, a lever and a link therefrom to one of said latter hinge members for raising and lowering it and the attached sash, said lever being foldable inconspicuously adjacent the sash, a pivoted drop latch on the un-hinged stile of the sash having a latch member extending laterally, and a receiving plate therefor on the wall-opening having an inclined cam slot extending deeply such as to be capable of manual release of the latch when the sash is in its raised position.

5. In building construction, a framed wall-opening; an inwardly-swingable panel therein; and means for forcing said panel transversely to its general plane and tightening the panel in the framed opening, including a footing-abutment to engage the inside lower margin of the latter, hinge members on the panel stile and mating hinge members on the framed opening, metal plate members on the latter carrying the mating hinge members, inclined cam slots in said metal plate members, headed pin fastening means for said latter hinge members movable up and down in said slots, a lever and a link therefrom to one of said latter hinge members for raising and lowering it and the attached sash, said lever being foldable inconspicuously adjacent the sash, a pivoted drop latch on the un-hinged stile of the panel having a laterally extending latch member, and a receiving plate therefor on the wall-opening having a slot to receive said latch.

6. In building construction, a framed wall-opening; an inwardly-swingable panel therein; and means for forcing said panel transversely to its general plane and tightening the panel in the framed opening, including a footing-abutment to engage the inside lower margin of the latter, hinge members on the panel stile and mating hinge members on the framed opening, metal plate members on the latter carrying the mating hinge members, inclined cam slots in said metal plate members, headed pin fastening means for said latter hinge members movable up and down in said slots, means for raising and lowering said movable hinge members and the attached panel, and a latch on the un-hinged stile of the panel capable of being released when the panel is in its elevated position.

7. In building construction, a framed wall-opening; an inwardly-swingable panel therein; and means for forcing said panel transversely to its general plane and tightening the panel in the framed opening, including a footing-abutment to engage the inside lower margin of the latter, hinge members on the panel stile and mating hinge members on the framed opening, metal plate members on the latter carrying the mating hinge members, inclined cam slots in said metal plate members, fastening means for said latter hinge members movable up and down in said slots, a lever and a link therefrom to one of said latter hinge members for raising and lowering the detached sash, said lever being foldable incon-

spicuously adjacent the sash, a pivoted drop catch on the un-hinged stile of the panel having a laterally extending latch, and a receiving plate therefor on the wall-opening having a slot to receive said latch.

8. In building construction, a framed wall-opening; an inwardly-swingable panel therein; and means for forcing said panel transversely to its general plane and tightening the panel in the framed opening, including a footing-abutment to engage the inside lower margin of the latter, hinge members on the panel stile and mating hinge members on the framed opening, metal plate members on the latter carrying the mating hinge members, means for mounting said latter hinge members thereon movable up and down and at the same time in inclined path, a lever and a link therefrom to one of said latter hinge members for raising and lowering the detached sash, said lever being foldable inconspicuously adjacent the sash, a pivoted drop catch on the un-hinged stile of the panel having a laterally extending latch, and a receiving plate therefor on the wall-opening having a slot to receive said latch.

9. In building construction, a framed wall-opening; an inwardly-swingable panel therein; and means for forcing said panel transversely to its general plane and tightening the panel in the framed opening, including a footing-abutment to engage the inside lower margin of the latter, hinge members on the panel stile and mating hinge members on the framed opening, means for mounting said latter hinge members to permit movement up and down and at the same time in inclined path, a lever and a link therefrom to one of said latter hinge members for raising and lowering the detached sash, said lever being foldable inconspicuously adjacent the sash, a pivoted drop catch on the un-hinged stile of the panel having a laterally extending latch, and means on the wall-opening coacting with said latch in its lowered and raised positions.

10. In building construction, a framed wall-opening; an inwardly-swingable panel therein; and means for forcing said panel transversely to its general plane and tightening the panel in the framed opening, including a footing-abutment to engage the inside lower margin of the latter, hinge members on the panel stile and mating hinge members on the framed opening, metal plate members on the latter carrying the mating hinge members, means for mounting said latter hinge members thereon movable up and down and at the same time in inclined path, and a lever and a link therefrom to one of said latter hinge members for raising and lowering it and the attached sash, said lever being foldable inconspicuously adjacent the sash.

11. In building construction, a framed wall-opening; an inwardly-swingable panel therein; and means for forcing said panel transversely to its general plane and tightening the panel in the framed opening, including a footing-abutment to engage the inside lower margin of the latter and being beveled downwardly and outwardly to a wedge a mating bevel on the lower margin of the said panel, hinge members on the panel stile and mating hinge members on the framed opening, and means for mounting said latter hinge members permitting movement up and down and at the same time in inclined path.

12. In building construction, a framed wall-opening; stops thereon; an inwardly swingable panel in said opening; and means for flatwise tightening the panel in the framed opening, in-

cluding a footing-abutment to engage the inside lower margin of the latter, inter-engaging packing means on the upper part of said panel and the frame opening, and hinge means mounting said panel for lateral swinging and for vertical inter-locking of said packing means.

13. In building construction, a framed wall-opening; stops thereon; an inwardly swingable panel in said opening; and means for flatwise tightening the panel in the framed opening, including a footing-abutment to engage the inside lower margin of the latter and being beveled to wedge a mating bevel on the lower margin of said panel, hinge means mounting said panel for lateral swinging and permitting vertical movement, and cam means forcing said panel transversely to its general plane against said stops.

14. In building construction, a framed wall-opening; stops thereon; an inwardly swingable panel in said opening; and means for flatwise tightening the panel in the framed opening, including a footing-abutment to engage the inside lower margin of the latter and being beveled to wedge a mating bevel on the lower margin of said panel, inter-engaging packing means on the upper part of said panel and the frame opening, hinge means mounting said panel for lateral

swinging and permitting vertical interengagement of said packing means, and cam means forcing said panel against said stops transversely to its general plane.

15. In building construction, a framed wall-opening; stops thereon; an inwardly swingable panel in said opening; and means for flatwise tightening the panel in the framed opening, including a footing-abutment to engage the inside lower margin of the latter and being beveled to wedge a mating bevel on the lower margin of said panel, hinge means mounting said panel for lateral swinging, and cam means forcing said panel transversely to its general plane against said stops.

16. In building construction, a framed wall-opening; an inwardly-swingable panel therein; and means for flatwise tightening said panel in the framed opening, including a footing-abutment to engage the inside lower margin of the latter, and means for mounting said panel for swingable vertical displacement and displacement flatwise within the framed wall-opening thereby tightening the panel against leakage at other points as well as at the footing-abutment.

HUBERT O. CARROLL.
